SERIES DISTILLATION PROCESS

Jean Loumiet et Lavigne, Itabo, Cuba

Application May 10, 1945, Serial No. 592,950
In Cuba May 25, 1944

2 Claims. (Cl. 196—73)

1

The invention relates to a method and apparatus for fractionally distilling petroleum or tar.

One object of the present invention is to provide a method for distilling petroleum, whereby the operations are carried out at very low pressures and temperatures in order to avoid cracking, and to extract the ingredient products in their most original chemical state.

Another object of the invention is to effect the recovery of the latent heat of evaporation as well as the sensible heat contained in the products of distillation, by causing water to absorb said heat to generate steam, and by applying the resulting steam for heating in the different distillation steps.

A further object of the invention is to effect all the heat transmissions with liquids into which is injected steam or inert gas, in the evaporating, heating or cooling of the products, and to heat the liquid-steam or gas mixture while flowing through externally heated tubes.

Another object of the invention is to provide in connection with each distilling phase, for the rectification of the vapor produced in that phase by means of the petroleum residue from the preceding distilling phase.

Another object of the invention is to provide a process of fractional distillation of petroleum utilizing heat recuperators wherein each successive distillation is effected under constant pressure and temperature conditions, and under a fluid injection which is also constant, the several constants being determined in accordance with the product desired.

According to the invention, the system includes generally a plurality of evaporating or distilling units connected in series and adapted to be operated at different pressures and temperatures but differing structurally only in diametric size, and from which vapors of different kinds are extracted in succession from the residue petroleum which is conducted from unit to unit until finally depleted of its desired products. In these units, a vapor current is injected at the bottom of each one of their tubes. The tubes of the calandria are contained in several sectors thereof of different cross-section and through which sectors heating vapors are conducted in succession from the large to the small sector to heat the tubes and the liquid and openings being so provided in the sector walls that the heating vapors alternatively from sector to sector pass in at the top and then at the bottom. The distilled vapors are collected in a dome or tank at the top of the evaporating unit and before passing to their out-

2

let are made to pass over a baffle or partition so that entrained oil particles will be adhered thereto and the baffle being positioned to cause the adhered oil particles on both top and the bottom sides thereof to be returned to the tank bottom and leave with the liquid residue.

The vapors from the last four evaporating units are directed through recuperators to recover the heat therefrom. This heat is returned to preceding evaporating units to heat the vertical tubes thereof through which the liquid is being passed. Other heat is used to warm the initial petroleum supplied to the first unit. Also recovery of heat is made in these recuperators of the final liquid residue. Adequate apparatus is provided throughout the system to rectify, separate and condense the resulting vapor products. The first units are heated from the exhaust steam of the pump engines.

Balance regulating means is provided for controlling the inflow of petroleum to the system. A continuously replenished quantity of liquid residue is weighed and mechanism is effected should its density depart from the desired set density to instantly alter the petroleum inflow.

A modified rectifier for first rectifying the produced vapor is provided wherein liquid residue from a preceding evaporating unit can be used as the rectifying medium. The rectifier includes a series of spiral coils about the evaporator casing and closed at their outer peripheries by a rectifier casing whereby to provide a spiral path for the vapors being cleaned and adjacent turns being in places alternately close together and farther apart so as to alter the velocity of the vapors traversing the path and to effect the separation of solid liquid particles by centrifugal action. The rectifying liquid is cascaded through apertures in certain loops of the coils to provide a curtain of the liquid in the vapor path through which the vapors will be forced and cleaned.

A modified arrangement of the evaporators is shown wherein space and piping is conserved. The last or high temperature evaporator is placed in the center and the other evaporators are nested about it. The domes of the several units are shaped and fitted to provide in appearance a single dome.

For other objects and a better understanding of the invention, reference may be had to the following detailed description taken in connection with the accompanying drawing, in which

Figs. 1 and 2 are respectively diagrammatic lay-out views of a petroleum distillation plant embodying features of the present invention;

3

Fig. 3 is a cross-sectional view, in elevation, of one of the evaporators;

Fig. 3a is a horizontal cross-sectional view taken at the station 3a—3a of Fig. 3;

Fig. 4 is a perspective view of a group of evaporators arranged for successive operation and with portions broken away to illustrate interior parts thereof;

Fig. 5 is a perspective view of half of the heat recovery apparatus or recuperators, the same being shown in section to expose the features therein.

Fig. 6 is an elevational view, partly in section, of a modified form of evaporator in which rectifying apparatus surrounds an evaporator and wherein the rectification is effected by passing the products resulting from the distilling process of the evaporator through petroleum remaining from that process.

Referring now particularly to Figs. 1 and 2, petroleum is forced into the system by a pump O, at the outlet of which is a by-pass valve By. Regulating mechanism is provided for operating the by-pass valve By in response to the density of the liquid residue. For this purpose, a float Fl is located in a container Zx, which is always kept full of the residue leaving the system through tube R₂. The control is set for a desired density of residue, and if this density is altered the valve By will be operated in response thereto to decrease or increase the inflow of petroleum to the system and thereby re-establish the desired density of the residues. Another form of control mechanism will be discussed hereinafter.

The petroleum is pumped through a pipe T to a tank A surrounding heat recuperators B₁ and B₂. On passing through tank A, the petroleum absorbs the heat radiated outwardly by the recuperator B₂ through an intermediate cylindrical wall. The petroleum leaves tank A through tube T and enters through tube T₁ into the first evaporator or distilling apparatus D₁ where are also injected at the bases of each one of the distilling tubes hydrocarbons forced from gasometers G_s by a blower Gv through tube Gt and regulated at its point of injection into the evaporator by a valve G₁.

Within the evaporator D₁ the petroleum is heated by exhaust steam from the steam engine which operates vacuum pump M and is conducted to evaporator D₁ by a tube St₃. A part of the petroleum will be evaporated. The vapors are collected in a tank Y₁ at the top of the evaporator and conducted through pipe V₁ to a rectifier U₁ to be purified. The vapors will surround the baffle X₁ and liquid still within these vapors which adheres to the baffle surface will be collected by the baffle and returned thereby to the lower part of tank Y₁.

The rectifier is the same as that disclosed in my U. S. Patent #2,230,255. A small amount of condensation is produced by cooling in the corrugated tube U₁ and this condensate trickles downwardly so that the distilled vapors upon passing upwardly and through the tube will come in contact with the condensate and be thereby rectified.

From the outlet of the rectifier the distilled vapors enter a centrifugal separator Z₁ of the type such as disclosed in my United States Patent 2,015,076, corresponding to my Cuban Patent 10,388, wherein any entrained liquid within the vapors is eliminated. From the separator Z₁ the vapors are passed through tube V₁ to a cooler E₂. The separated liquid from Z₁ is reinjected into the evaporator through tube t₁ extending down

4

the side of the evaporator D₁ to the lower part of the evaporator to join with the initial supply pipes T and T₁. A valve r₁ controls the supply of the vapor to the tube V₁.

In the cooler E₂ a large part of the vapors coming from the evaporator D₁ are condensed, the mixed condensed liquid and uncondensed vapors are conveyed to separator F₁ through pipe L₁. The separated liquid passes to another cooler E₁, where it loses part of its heat, and then is passed through a pipe P₁, Fig. 1, to a storage reservoir, not shown. The gas from separator F₁ is passed to the gasometer G_s by a tube G.

The liquids from the tank Y₁ and the rectifier U₁ of evaporator D₁ are drained therefrom by tubes t₂, T₂, Fig. 2, and conducted to a second evaporator D₂. The tube T₂ is in the form of a siphon so that in case of absence of liquid in tank Y₁ vapor is prevented from entering the evaporator D₂.

The liquid which enters evaporator D₂ is similarly injected at its entrance to evaporator D₂ with the hydrocarbons pumped from gasometer G_s by blower Gv. A valve G₂ regulates the supply of hydrocarbons to the evaporator D₂. Evaporator D₂ is heated, the same as D₁, by exhaust steam from the steam engine which runs the vacuum pump M and conducted to the evaporator D₂ through the same tube or pipe St₃.

A second distillation of the petroleum now takes place. The distillation is effected in all the evaporators from D₂ to D₇, in the same manner that it is effected in D₁. These other evaporators are of similar construction, except that they are reduced in size as the volume of the petroleum is reduced due to evaporation, and thereby to maintain approximately the same velocity of flow in the evaporator tubes. The vapor in D₂ passes over baffle X₂ and to the rectifier U₂, separator Z₂, valve r₂, tubing V₂, condenser E₂, separator F₂. From the separator F₂ the liquid passes through cooler E₁ and tubing P₂ to a reservoir. The non-condensed gases or vapor from separator F₂ pass through tubing G to the gasometer G_s.

Petroleum which was not distilled in D₂ passes through siphon tube T₃ to the evaporator D₃ where it receives a new injection of gas coming from the gasometer G_s and regulated by valve G₃. This evaporator D₃ is heated by a vapor, produced in recuperator B₂ by the products from the following phases of distillation, and conducted to evaporator D₃ by the tubing St₂.

The vapor produced in D₃ containing the injected gas leaves through the rectifier U₃ and passes through separator Z₃, tube V₃ and condenser E₂, pipe L₃, separator F₃ and cooler E₁. From cooler E₁, the cooler liquid passes through pipe P₃ to the reservoir. Gas separated in F₃ passes through tubing G to the gasometer G_s.

Starting with D₄ the fluid injected in the petroleum entering in the tubes of the successive evaporators is constituted by exhaust steam from the steam engine of the vacuum pump M by way of the tubing St₃. The evaporator D₄ is heated by vapor produced in the recuperator B₁ and conducted thereto through the tubing St₁.

The vapor from the tank Y₄ passes through rectifier U₄, separator Z₄ but instead of passing from the separator through the cooler E₂ as in the case of the preceding evaporators just described, is conducted through pipe V₄ to the recuperator B₂ where it will be condensed. At the outlet of the recuperator B₂ mixed vapor and liquid are conveyed by pipe L₄ to cooler E₄, Fig. 1,

and separator F₄. The separated liquid passes down through tube P₄ through cooler E₃ and then to the reservoir. The separated vapor passes up through tube H and governor valve I to be treated together with vapors from separators F₅, F₆, F₇, in a manner to be shortly described.

The evaporators D₅, D₆, and D₇ are heated by high pressure live steam delivered to the same through tubing S_t. While only one live steam tubing is shown it shall be understood that several steam generators may be utilized so that different high steam pressures can be used for the different evaporators D₅, D₆, and D₇, with the higher pressure being in D₇.

The vapors produced by these evaporators D₅, D₆, and D₇ are conveyed by separate tubing V₅, V₆ and V₇ to the recuperator B₁ where they are condensed and cooled and then passed through tubes L₅, L₆, L₇ to coils in recuperator B₂ for further cooling. From the recuperator B₂ the vapors and condensed liquids pass through extensions of tubes L₅, L₆ and L₇ to cooler E₄ and the separators F₅, F₆ and F₇. In the recuperators, heat is recovered from the vapors and the condensed liquids. The liquids separated in the respective separators leave through tubes P₅, P₆ and P₇ which pass through cooler E₃ and deliver the liquids to the reservoirs. The separated vapors are drawn along with vapors from F₄ by the vapor injector I operated by exhaust steam from line S_t and are discharged thereby into a barometric condenser C. The vacuum created by this operation is transmitted to separators F₄, F₅, F₆ and F₇ and is controlled by valves in the individual pipes connecting the pipe H with the separators.

Between the injector I and condenser C is a small rectifier J into which a small quantity of water is injected to cool the vapors and insure liquefaction of all of the petroleum vapors. Only the water vapor which was injected in the petroleum will remain in the vapor state. In most cases, the passing of air or water over the outside of the rectifier will be sufficient to condense all of the petroleum vapors but in rare cases the injection of water, is desirable. At the outlet of the rectifier J is a centrifugal separator K which removes the liquid products from the rectifier J. This liquid is conducted through a tube n to the evaporator D₆ by way of the syphon tubing T₆.

The recuperator B₁ is heated by the vapors produced in the evaporators D₅, D₆, and D₇ and conducted to the same through tube V₅, V₆ and V₇ and also by means of the residue from the last evaporator, D₇ which passes from tank Y₇, through tube R to recuperator B₁. Recuperator B₂ is heated by the same fluids which heat the recuperator B₁ and also by the vapors produced in the evaporator D₄ and conducted by tubing V₄ to recuperator B₂.

By injecting exhaust steam into the small tube R at m by means of tube S_t, the nature of the residue liquid in tube R is modified. A gas or vapor in a small or medium diameter tube containing liquid, occupies the central part and forces the liquid against the walls to provide an annular part. The liquid is spread out thin and is thus more readily heated by the gas or vapor and that increases its heat transmitting effect. At the same time the velocity of the liquid is increased and that increases the heat transmitting effect of the liquid. The form of the steam and liquid within tube R is maintained even though the tube becomes horizontal, as in

the recuperator B₁. In this way, heat is added to the recuperators, and their efficiency is accordingly increased.

The condenser C receives cold water from pump N through pipe W. Heated cooling water leaves the condenser C through a large pipe N' and is delivered to a reservoir N'' located adjacent the pump N. The non-condensable gases are removed from the condenser through tube q and vacuum pump M. The pump N not only supplies cool water to the condenser but also supplies cooling water to the various coolers E₁, E₂, and E₃ and E₄. The water circulates from the pump N through tubing W₁, cooler E₁, tubing W₂, cooler E₂, tubing W₃, cooler E₃, tubing W₄, cooler E₄, and tubing W₅ back to reservoir N''.

It will be apparent that instead of two recuperators, three or four may be used, each operated by the fluids which heat the preceding recuperators and with condensate from the first evaporators, as well as from the latter evaporators, as in the case just described.

The blower G_v forces the gases from gasometer G_s through the evaporators D₁, D₂, and D₃ and various other equipment associated therewith and back to the gasometer G_s. Gases join with the vapors produced in these evaporators and are returned from separators F₁, F₂, F₃ to gasometer G_s by pipe G. The pipe G_t is connected to the pipe G_t and upon turning the valve g₁ excess gas may be drawn from the gasometer system.

Referring now to Fig. 3, a single evaporator is shown. Petroleum enters the evaporator through tube T at the bottom and rises in a chamber g above the same to the open bottom ends of vertically extending tubes a. Treating vapor enters through the pipe SG and the nozzle arrangement f lying within chamber g which has a nozzle cover e with a plurality of spouts d respectively aligned with the open bottom ends of the tubes a. Through these spouts treating vapors are injected into the evaporator and the liquid is treated at the bottom ends of the tube a. Pipe p connects with the nozzle arrangement f to permit cleaning when necessary.

At the upper part of the calandria is tank Y in which the produced vapors are separated from the liquid. This liquid leaves the lower part of the tank Y through the pipe T' while the vapors leave tank Y through the pipe V located in the upper part thereof above a baffle wall X. Such liquid as is collected in the baffle X is returned to the lower part of the tank Y through a drain x. A skirt portion y prevents the direct entrance of the distilled vapors and liquid particles into pipe V which are drawn to the top of the baffle X. A cover h is disposed over an opening in the top of the tank through which the baffle and tank can be cleaned.

The calandria D is divided into a central sector and several peripheral sectors through which the heating vapor circulates alternatively upwardly and downwardly. The cross-sectional area of the chamber through which the heat vapor is first passed is the largest of all the sectors and the remaining sectors decrease in size as the heat vapor moves toward the smallest sector. Condensate is drawn from the bottom of the sectors by drain means not shown.

A closure plate k for supporting the lower ends of the tubes a is carried on the housing g and secured thereto by a flange on evaporator casing D. A similar plate k is disposed on the upper

end of the casing D and secured by tank Y. Vertically extending partitions b divide the interior of the casing into sectors and in these partitions are openings c₁, c₂ and c₃ for permitting the flow of the heated steam between sectors. Steam entering through St, Figs. 3, 3a, rises in the first sector and leaves it through opening c₁. The steam then enters the central sector, moves downwardly, and leaves through opening c₂ to enter a second peripheral sector. In the latter sector, it moves upwardly and enters the next peripheral sector through opening c₃. The steam moves through the remaining sectors in this manner and through other openings, not shown.

Referring now to Fig. 4, there is shown a novel arrangement of the evaporators wherein all of the various evaporators are consolidated or nested into a more or less single unit. The evaporator D₇ operating at the highest temperature is located in the center and the other six evaporators surround the evaporator D₇. The tanks at the top of the apparatus are constructed so as to appear as one single dome. The cup shaped chambers g are left round. The spaces between them may be filled with asbestos or other insulating material to limit the loss of heat. Similar lettering and numerals are given to this arrangement as given to the line arrangement shown in Fig. 2.

Referring now to Fig. 5, the details of the recuperators are more clearly shown. The inner recuperator B₁ produces a vapor of higher pressure and temperature than the outer recuperator B₂. Both of the recuperators are cylindrically shaped and are closed at their ends by flat cover plates. The heated vapors which operate these recuperators pass through horizontal coils. A perforated plate p placed near the upper cover divides the recuperator B₁ into two parts, a lower part containing the heating coils, and an upper part receiving the water upon being returned from the calandrias. The perforations in the plate p are such as to always maintain a small depth of water in the upper part. The water leaving through the perforations contacts the first horizontal coil and maintains a thin layer of water over the same. In this manner, the water drips from coil to coil and layers of water are formed over all of the coils from the top to the bottom of the recuperator. The vapor produced rises between the coils and leaves the recuperator through the pipe S₇. Recuperator B₂ almost completely surrounds the recuperator B₁ and is constructed in a similar manner. Vapors from D₇ are conducted by tube V₇ to the first of two horizontal coils S_{p7}. The diameter of the pipe decreases with each coil throughout the entire length of the coils. The small end of the bottom coil connects by tube L₇ with coil S₇ in recuperator B₂. From recuperator B₂ the vapors pass as above described, in connection with Figs. 1 and 2.

Vapors from D₆ are conducted by tube V₆ to similar horizontal coils S_{p6} in B₁ and then through tube L₆ wound into coil S₆ in recuperator B₂ from which they are passed in a manner as above described.

Vapors from D₅ are conducted by tube V₅ to coils S_{p5} in B₁ and leave the same through tube L₅ wound into coil S₅ in B₂ and passing to other parts of the system as above described. Thus, in the manner just described, the vapors from evaporators D₅, D₆ and D₇ are respectively conducted through horizontal coils S_{p5}, S_{p6} and S_{p7} of recuperator B₁ and horizontal coils S₅, S₆, and S₇ of recuperator B₂. The liquid residue from

tank Y₇ of the last evaporator D₇ is passed through pipe R to four horizontal coils S_{pR} in recuperator B₁ and then through pipe R₁ to three horizontal coils S_{IR} in recuperator B₂. The residue leaves recuperator B₂ through pipe R₂. Recuperator B₂ is further heated by vapors from evaporator D₄ passed thereto by pipe V₄ and entering horizontal coils S_{p4} thereof and leaving through L₄, Fig. 1. All vapors are substantially condensed before leaving recuperator B₂.

The recuperator B₂ is surrounded by tank A through which the petroleum used in the operation is passed at a low velocity so as to reduce as much as possible the loss of heat through the cylindrical surface of the recuperator B₂. Such loss is thus utilized by heating the petroleum being distilled. All of the apparatus is highly insulated wherever possible to avoid loss of heat. Thus, usable heat is recovered from the evaporators D₄, D₅, D₆ and D₇ by the recuperators B₁, B₂.

Referring now to Fig. 6 there is shown a modified form of rectifier for rectifying the vapors resulting from each distilling phase, in which the rectifier is made concentric with the evaporator so that the products resulting from the fractional distillation in that evaporator are rectified therein. This rectifier comprises generally a spiral coil having loops s surrounding the upper part of the evaporator calandria D_{n+1}, a spiral coil having loops p surrounding the lower part of the calandria and an outside casing RC surrounding the coils S, and the evaporator calandria. The coil loops are thus supported between the evaporator calandria and the outside casing RC.

Vapors produced in the calandria D_{n+1} leave the dome or tank Y_{n+1} through tube V_{n+1} and are delivered to the lower end of the casing RC. In the casing the vapors pass upwardly through the spiral paths provided between loops p and S. The loops p of the coils are not of equal distance apart throughout the length of the coils whereby the cross-section of the spiral path diminishes and increases at intervals throughout its length thereof.

The residue liquid from the preceding evaporator is supplied to the third pair of loops p from the bottom by tube T_{n+1} which enters the casing RC and delivers the liquid throughout a container to the lower loop of that pair. This liquid flows lengthwise of the spiral constituted by the successive loops p, but that flow is broken and liquid falls through the openings r to the immediate lower loop p, forming a cascade across the full width of the loop p. In this manner, the vapors are forced to pass through those cascades, atomizing the liquid, and entering into intimate contact with the atomizing liquid, to cause rectification of said vapors. These apertures r are located in the constricted area of the path and where the velocity is at a maximum. Upon leaving this point of high velocity, the vapors are passed to the area of greater cross-section and their velocity is decreased. Liquid particles are projected against the wall RC by centrifugal force and will adhere to it and descend down the wall surface onto the outside of the loop and rearwardly along said loop to join the rectifying liquid. The vapors are accordingly freed each turn in the path by this centrifugal action upon the liquid particles.

Loops p are inclined downwardly from its outer periphery toward its inside periphery so as to distribute the liquid uniformly over the loop during its passage downward over the same.

This operation proceeds in the same manner throughout the upper loops P of the lower coils. The rectifier liquid for the loop is the liquid separated from the upper coil of loops S. The same is drained from the loops S and dropped on the upper loop P. Slight cooling which is effected through the walls causes condensation in the region of the upper coils. This condensation will leave the rectifier with the rectifying liquid. A channel *m* on the inner peripheral face of the wall RC and extending in a direction intermediate the direction of vapor flow and a vertical direction conducts the separated liquid to the lower part of the upper separator for deposit upon the lower loops *p*. Liquid is picked up by channel *m* at all turns along the height of coil of loops S. The loops S instead of inclining downwardly from the outside toward the inside incline downwardly from the inside toward the outside, and upon nearing the outside they incline abruptly so as to form with the wall RC an outer channel S'' following the loops S and extending through the length of the coil. The liquid particles projected against the wall RC by centrifugal force descend along said wall in this channel S'' which empties either into wall channel *m* or directly at its bottom end. The rectified vapor leaves the rectifier through tube V' n+1 and passes to a recuperator. The rectifying liquid leaves the rectifier through the pipe T' n+1 and is injected into an adjacent evaporator.

The general use of steam as the heat transmitter in each distilling step, makes it possible for each step to be independently controlled and regulated in accordance with the products desired from each step. The pressure applied in each step and the amount of gas or vapor injected are maintained constant once they are set. With a constant temperature, constant pressure, constant quantity of fluid injected, and constant velocity of the fluid through the apparatus, the homogeneity of the products is maintained. If the composition of the petroleum varies and the same products are still desired, one or more of these conditions can be altered to adapt the process to the new petroleum.

To maintain a constant steam output of the recuperators, live steam may be added to bring the recuperator steam to the desired pressure and temperature. I have described what I believe to be the best embodiments of my invention. I do not wish, however, to be confined to the embodiments shown, but what I desire to cover by Letters Patent is set forth in the appended claims.

I claim:

1. In a fractional distillation process of distilling a complex liquid comprising passing said liquid successively through a plurality of stills while maintaining said stills at various temperatures, the lower temperatures being in the initial group of stills and the higher temperatures in the ter-

5 minal group of stills, passing the distillate vapors from the terminal group of stills and the final residue from the last still into heat exchange relationship successively with a first and a second stream of heat exchange liquid to vaporize each of said streams to produce vapors at different temperatures, heating the last still of the initial group by the first vapor stream and heating the next to the last still of the initial group by the second vapor stream.

15 2. In a fractional distillation process of distilling a complex liquid comprising passing said liquid successively through a plurality of stills while maintaining said stills at various temperatures, the lower temperatures being in the initial group of stills and the higher temperatures in the terminal group of stills, passing the distillate vapors from the terminal group of stills and the final residue from the last still into heat ex-

20 change relationship successively with a first and a second stream of heat exchange liquid to vaporize each of said streams to produce vapors at different temperatures, heating the last still of the initial group by the first vapor stream and heating the next to the last still of the initial group by the second vapor stream, and passing the vapors generated in the last said still of the initial group in heat exchange relationship with said second stream of liquid.
